T. S. Lambert.

UNITED STATES PATENT OFFICE.

T. S. LAMBERT, OF PEEKSKILL, NEW YORK.

IMPROVEMENT IN MODE OF FACING THE WALLS OF BUILDINGS.

Specification forming part of Letters Patent No. 40,844, dated December 8, 1863.

To all whom it may concern:

Be it known that I, T. S. LAMBERT, of Peekskill, Westchester county, New York State, have invented a new and Improved Method of Facing the Walls of Buildings; and I do hereby declare that the following is a full and exact description of the same, reference being had to the accompanying drawings and the figures marked thereon.

The nature of my invention consists in constructing the material to be used for facing with a shoulder or offset to be placed between the brick of the wall as it goes up, and to be held in its place by them.

Figures 1, 2, 3, 4 represent such shoulder, offset, or armature, marked *b*. In Fig. 4 the facing is represented as laid upon one side of a wall. It might be placed on the other side, or upon both sides in a similar manner. Figs. 5 and 6 represent face views of a portion of wall laid up, as in Fig. 4. Figs. 2 and 3 represent that the arms or offsets may be at either or both ends, and they may also be in the middle and also transverse. They may extend entirely across the facing or be made at intervals only. They may also be perforated.

The facing may be made of any desirable material; but practically it may be best made of clay in some of its forms. Four and one-half inches by eight inches by one-half an inch to an inch thick for each piece of front facing, with an offset four inches by eight by half an inch thick will be the most practical for ordinary purposes. The facing should be bedded

against the wall with hydraulic cement, to prevent the admission of any water, though ordinary mortar will answer.

The front of the facing may be made smooth or with any device, and glazed or unglazed, though practically it will be best if glazed, requiring then no expense for keeping it in repair. It may be used for finishing the inner as well as the outer surface of walls; and if porcelain is used, either plain or ornamented with gilding, a far more beautiful and resplendent finish can be obtained than is had by the use of marble, and at much less expense.

The pieces of facing may be made with a square or diamond shaped front, and with the shoulder extending diagonally. Other shapes may be given and the shoulders otherwise placed, and a mosaic work by means of different-colored pieces of facing obtained, which shall exhibit exceeding beauty of coloring and design.

What I claim as my invention, and desire to secure by Letters Patent, is—

The construction of facing for the inner or outer surface of walls of buildings, each piece of which facing is furnished with a shoulder, offset, or arm, to be the means of fastening it to the walls, in the manner and for the purpose substantially as set forth.

T. S. LAMBERT.
